URINAL SEAM COVER FASTENING DEVICE

Gordon P. Gavin, Kohler, Wis.

Application March 13, 1939, Serial No. 261,455

4 Claims. (Cl. 4—104)

My invention relates to improvements in urinal seam cover fastening devices of a type adapted to secure seam covers on urinals.

Urinals, particularly of the stall type, are frequently installed in batteries of two or more and a china seam cover is used to cover the space or seam between adjacent urinals.

It is conventional practice to cement this seam cover in position. This operation takes a great deal of time and skill for a satisfactory result and has a further disadvantage that, once the installation is made and the cement set, the seam cover can be removed only with extreme difficulty, a serious handicap when it is desired to replace a urinal or some other contingency requires the removal of one or more of the urinals.

It is the object of the present invention to provide means whereby said seam covers may be securely attached to the urinals yet may readily be removed, all with the expenditure of but little time or skill.

It is a further object of the invention to provide means whereby said seam covers may be attached in a sightly and sanitary manner.

With the foregoing and related objects in view, the invention consists in the arrangement illustrated in the accompanying drawing, in which Figure 1 is a perspective view of a pair of urinals with seam cover installed in accordance with the present invention; Figure 2, a sectional view thereof taken along the lines 2—2 of Figure 1; and Figure 3, a front view of a portion of the seam cover.

In the drawing, the numerals 1 and 2 indicate, respectively, a pair of urinals, mounted in adjoining but spaced relationship.

A seam cover 3 of L shape is adapted to cover the seam or space between the urinals 1 and 2. The urinals 1 and 2 are formed with plane side surfaces 4 and 5 terminating, at their front and upper edges, in outstanding flanges 6 and 7.

The seam cover fastening devices, indicated generally by the numeral 8, are suitably positioned to hold the seam cover in place. Preferably two of such devices are used, one in the front and one on top of the seam cover, as illustrated in Figure 1.

The seam cover fastening device comprises a bolt 9 preferably having a screwdriver slotted head 10, a nut 11 having threaded connection therewith and a spring metal strip 12 suitably apertured to allow the bolt 9 to pass therethrough. The metal strip 12 is provided with a pair of wings 13 and 14 disposed at an acute angle to the bolt 9, thus the strip is in substantially a

V shape with the open end of the V facing the head 10 of the bolt 9.

The seam cover 3 is provided with an aperture through which the bolt 9 extends, the bolt head 10 abutting the seam cover preferably within a recess 16 therein.

To install the seam cover it is necessary only to place the seam cover and fastening devices in position. The strip 12, being of spring metal, when pushed against the urinals, springs sufficiently to allow it to enter between the urinals, then springs outwardly to contact the surfaces 4 and 5. The bolt 9 is then rotated, by means of the slotted head 10, until the nut 9 forces the strip 12 into contact with the flanges 6 and 7, drawing the seam cover 3 into firm engagement with the urinals 1 and 2.

If desired, the recess 16 may be filled with cement and a cap 17 may be placed thereover as illustrated, or the head 10 may extend to the face 20 of the seam cover, depending on the ornamental characteristics desired.

The seam cover may readily be removed by turning the bolt 9 to relieve the tension created by the pressure of the nut 11 on the strip 12.

It will thus be seen that the seam cover may be attached or detached in a few moments and that the services of a skilled workman are not required either to attach or to detach it.

The entire assembly is sightly and, since the seam cover is drawn tightly against the urinal leaving no space or crack through which liquid may pass, is more sanitary than a cemented connection, cement being somewhat absorbent.

The specific details herein disclosed are for the purpose of illustration only as various modifications thereof may be made without the exercise of invention and the invention is not limited thereto but embraces all devices within the scope of the appended claims.

I claim:

1. In a urinal and seam cover assembly, the combination of a pair of urinals positioned in adjacent, spaced relationship, said urinals having their adjacent sides in the form of a plane surface terminating at its front and upper edge in an outstanding flange, a seam cover adapted to overlie the adjacent portions of said urinals and to close the space therebetween, and means for attaching said seam cover to said urinals, said means comprising a bolt extending through said seam cover, a strip of spring metal apertured to allow said bolt to pass therethrough and comprising a pair of wings disposed at an acute angle to said bolt and adapted to abut the aforesaid

flanges of said adjacent urinals and a nut threaded on said bolt and adapted to be drawn thereby into abutment with said spring strip.

2. In a urinal and seam cover assembly, the combination of a pair of urinals positioned in adjacent, spaced relationship, said urinals having their adjacent sides in the form of a plane surface terminating at its front and upper edge in an outstanding flange, a seam cover adapted to 10 overlie the adjacent portions of said urinals and to close the space therebetween, and means for attaching said seam cover to said urinals, said means comprising a bolt extending through said seam cover, a strip of spring metal apertured to 15 allow said bolt to pass therethrough, said strip being of substantially V shape with the open end of the V facing the head of said bolt and the ends of said strip adapted to abut the aforesaid flanges of said adjacent urinals, and a nut threaded on said bolt and adapted to be drawn thereby 20 into abutment with said spring strip.

3. In a urinal and seam cover assembly, the combination of a pair of urinals positioned in adjacent, spaced relationship, said urinals having their adjacent sides in the form of a plane surface terminating at its front and upper edge in an outstanding flange, a seam cover adapted to 25 overlie the adjacent portions of said urinals and to close the space therebetween, and means for attaching said seam cover to said urinals,

said means comprising a bolt extending through said seam cover, a strip of spring metal apertured to allow said bolt to pass therethrough, the ends of said strip being adapted to abut the aforesaid flanges of said adjacent urinals, and a nut threaded on said bolt and adapted to be drawn thereby 5 into abutment with said spring strip.

4. In a urinal and seam cover assembly, the combination of a pair of urinals positioned in adjacent, spaced relationship, said urinals having their adjacent sides in the form of a plane surface terminating at its front and upper edge in an outstanding flange, a seam cover of L-shaped configuration adapted to overlie the adjacent portions of said urinals and to close the 10 space therebetween and a plurality of means for attaching said seam cover to said urinal, at least one of said means being positioned on top of said seam cover and at least one of said means being positioned on the front of said seam cover, said 15 means comprising a bolt extending through said seam cover, a strip of spring metal apertured to allow said bolt to pass therethrough, said strip being of substantially V shape with the open end of the V facing the head of said bolt and the 20 ends of said strip adapted to abut the aforesaid flanges of said adjacent urinals, and a nut threaded on said bolt and adapted to be drawn thereby 25 into abutment with said spring strip.
